UNITED STATES PATENT OFFICE

2,503,795

ROAST RACK

John Clark Brown, Upper Montclair, N. J.

Application December 1, 1948, Serial No. 62,797

4 Claims. (Cl. 99—426)

1

This invention relates to improvements in roasting racks whereby a roast or the like can be supported upon and in spaced relationship to a pan in an oven whereby it can be conveniently handled inasmuch as such devices are usually in the general shape of a cradle in which the roast is confined between swingable side members attached to a base member.

More specifically a cradle-shaped roast rack of the kind herein contemplated comprises as main members:

A base member having leg or spacing portions whereby it is spaced from a supporting plane, and a pair of side members attached to the base member in such a manner that they can be bodily adjusted towards and away from each other and positioned in an outwardly inclined roast-receiving position to suit the size of the roast. The side members are foldable or collapsible flat upon the base member from their roast-supporting position so that the device may be compactly stored when not in use.

The improvements of this invention apply to a roasting rack of the kind that may herein be termed an all-wire construction, that is a wire construction which offers sufficient support for the roast but yet due to the wire construction has at most only line contacts with the roast and therefore maintains the roast substantially entirely exposed although sufficiently supported.

The aforementioned main members of such a roasting rack, and especially the base member which supports the roast at the bottom, have been known to be of a grid-like wire construction composed of individual lengths of wire or rods joined together at points of intersection as by welding, brazing or the like, to constitute grid-like structures in which straight lengths of wire appear to be thus connected or joined at right angles to a marginal or frame wire. In other words, such a known construction represents a grid pattern of substantially straight rods or wires intersecting at right angles and having their intersecting points secured as above stated.

It is among the objects of this invention in such all-wire roasting racks to avoid all welding or brazing connections; to provide an all-wire construction that differs from the conventional grid pattern and presents a pleasing pattern of simple lines or curves capable of supporting the roast cradle-like effectively yet by a minimum of contact points or lines; and to provide an all-wire roasting rack construction that is simple and inexpensive to produce and can be constructed from a minimum length of wire material.

2

These objects are attained by providing special preformed wire shapes or component shapes of the rack construction, which shapes in themselves are integrated, consisting of a continuous length of wire, and by swedge-connecting such component wire shapes with one another in a certain manner.

More specifically these objects are attained by providing a base member comprising a pair of identical specially shaped wire loop portions symmetrically disposed with respect to each other with the outer ends of the loop portions being bent downwardly to represent wide leg portions at the open ends of the roasting rack.

According to another aspect of this invention the base member is shaped from wire material so as to give the overall appearance of an I-shape, that is a shape having a constricted longitudinal body portion and transversely extending end portions, the intermediate or body portion extending in a horizontal plane while the end portions extend in vertical planes parallel to each other.

Features lie in the specific wire-shaping or configuration of the base member.

25 A specific feature lies in the configuration of a wire loop member as an article of manufacture two of which combined in symmetrical fashion constitute the base member.

In the drawings:

30 Fig. 1 is an end view of the roasting rack with the side members indicated in various adjusted positions, and showing the corner portions of the base member swedge-pinched to provide outer end stops for the extreme outer positions of the side members.

35 Fig. 2 is a side view of the roasting rack taken on line 2—2 of Fig. 1.

Fig. 3 is a plan view of a roasting rack taken on line 3—3 of Fig. 2.

40 Fig. 3a is a transverse section on line 3a—3a in Fig. 3.

Fig. 4 is an enlarged perspective view of one of the swedge-pinched corner portions of the base member.

45 Fig. 5 is a top view of the base member of the roasting rack showing the component portions thereof drawn apart.

Fig. 6 is an end view of the roasting rack in folded condition.

50 Fig. 7 is a top view of the folded roasting rack taken on line 7—7 of Fig. 6.

Fig. 8 is an overall perspective view of the roasting rack in unfolded or operating condition.

The roasting rack comprises three main members each of which is in the nature of a wire

frame or shaped wire structure, to wit: a base member 10, and a pair of side members 11 and 12 hinged to the sides of the base member. The base member 10 has an overall length L and an overall width W and in plan view it has the overall appearance of an I-shape presenting a longitudinally and medially extending constricted body portion B and transverse or wide end portions E₁ and E₂.

In this embodiment the base member 10 is composed of a pair of identical loop members 13 and 14 interconnected by means of a medially disposed and longitudinally extending sleeve member 15 swedge-connected to the loop members 13 and 14. The loop member 13 comprises an outer or wide head portion 16 (see Figs. 5 and 8) which is represented by a shaped wire portion extending in a vertical plane and in fact constituting the end portion E₁ of the base member 10, and further comprises an inner or narrower leg portion 17 extending in a horizontal plane and consisting of a pair of legs 18 and 19, each leg having an intermediate offset 18^a and 19^a respectively so as to form outer leg portions 18^b and 19^b respectively which are horizontally spaced from each other a distance d₁ and to form inner or terminal leg portions 18^c and 19^c adjoining or contiguous to each other.

The head portion 16 of the loop member 13 extends in its vertical plane downwardly from the horizontal plane of the leg portion 17 and thereby places the leg portion 17 a distance d₂ from a supporting plane or supporting pan indicated at P. The head portion 16 of loop member 13 comprises a horizontal portion 20 at the bottom which merges at each end through bends 21 and 22 with vertical portions 23 and 24 respectively which vertical portions in turn merge with bends 25 and 26 respectively which bends are of inverted U-shape extending upwardly as well as inwardly and towards each other in the vertical plane. The width of bend 25 is designated as u₁ and its height as h₁. The width of bend 26 is designated as u₂ and its height as h₂. These U-shaped bends 25 and 26 in turn merge through bends 27 and 28 respectively with horizontal portions 29 and 30 respectively which further extend towards each other, all in the vertical plane. However, at their inner ends the horizontal portions 29 and 30 merge through horizontal bends 31 and 32 respectively with the aforementioned legs 18 and 19 respectively which legs extend in the horizontal plane. The loop member 14 is identical to the loop member 13 just described and is disposed in symmetry therewith so that both loop members 13 and 14 together with the sleeve member 15 interconnecting them may constitute the base member 10. The connection between the sleeve member 15 and two pairs of terminal leg portions of the two loop members 13 and 14 is further secured by spot-swedging, that is, by a pair of swedged-in depressions or transverse notches 33 and 34.

Consequently the loop member 14 comprises a head portion 35 (see Figs. 5 and 8) extending in a vertical plane and a leg portion 36 extending in a horizontal plane. The head portion 35 comprises a horizontal wire portion 37 at the bottom, and a pair of vertical portions 38 and 39 at the ends of the horizontal portion 37 and merging therewith through bends 40 and 41. The vertical portions 38 and 39 merge with bends 42 and 43 respectively of inverted U-shape extending upwardly as well as inwardly, that is towards each other to merge with horizontal portions 44 and

45 respectively which in turn extend further inwardly and towards each other. The horizontal portions 44 and 45, however, merge through horizontal bends 46 and 47 with horizontally extending legs 48 and 49 respectively which in turn have inward offsets 43^a and 49^a respectively dividing the legs into outer leg portions 48^b and 49^b spaced a distance d₃ from each other and inner leg portions 48^c and 49^c adjoining one another and surrounded by and secured to the sleeve member 15.

Looking at the base member 10 as a whole there are thus provided the inverted U-shaped bends 25 and 26, 42 and 43, one such bend being disposed at each corner of the base member to provide points of hinge attachment for the side members 11 and 12. That is to say a pair of such bends 25 and 42 serves for the attachment of the side member 11 while the pair 26 and 43 of these bends serves for the attachment of the side member 12. In this way the side members are swingable about a pair of horizontal longitudinal axes which are parallel to each other as well as parallel to the medial or longitudinal body portion B of the base member.

In order to determine the extreme outwardly inclined position of the side members 11 and 12 the bends 25 and 26, 42 and 43 are swedge-pinched to provide inwardly extending deformations 25^a, 26^a, 42^a, 43^a respectively (as exemplified in the detail perspective Fig. 4) in order to thereby provide stops for the side members 11 and 12.

The one side member 11 comprises an intermediate or body portion 50 having a U-shaped bend or middle portion 50^a the extent or depth of which is designated as D₁ and the width of which is designated as T₁, and further having a pair of shanks or end portions 51 and 52 extending at right angles from the body portion 50 and merging therewith as through bends 53 and 54 respectively. The shanks 51 and 52 terminate in eyes 55 and 56 respectively formed by the wire being looped or bent around the corner wire portions of the base member which corner portions have been identified as the inverted U-shaped bends 25 and 42.

Similarly, the other side member 12 comprises an intermediate or body portion 57 having a U-shaped middle portion or bend 57^a the extent or depth of which bend is designated as D₂ and the width as T₂, and further having a pair of shanks or end portions 58 and 59 extending at right angles from the body portion and merging therewith as through bends 60 and 61 respectively. The shanks 58 and 59 terminate in eyes 62 and 63 respectively formed by the wire of the shanks being looped around the respective corner portions of the base member which corner portions have been identified as the inverted U-shaped bends 26 and 43.

Referring to Fig. 1 it will be seen that the side members 11 and 12 are bodily and slidably adjustable upon the base member 10 and relative to each other. That is, the side members are adjustable towards and away from each other by being slidable to the extent of the length of the horizontal portions 28, 30, 44, and 45 of the base member, that is inwardly to stopping points defined by the horizontal bends 31, 32, 46, 47 of the base member. In this way the distance between the side members can be adjusted to the size of the roast that is to be placed between them.

I claim:

1. A roast rack having a wire frame base member and a pair of wire frame side members each of

which is hinged to a respective pair of corners of the base member so that they can be swung towards and away from each other and about axes substantially parallel to each other and parallel to the longitudinal median line of the base member characterized by the fact that the base member comprises a pair of symmetrically disposed wire loop portions each of which in turn comprises a wide head portion extending transversely of said longitudinal median line of the base member and in a substantially vertical plane, and a narrow leg portion extending in a substantially horizontal plane from said vertical plane whereby the leg portions of the loops constitute a relatively narrow longitudinally and medially extending body portion of the base member, and said head portions constitute relatively wide transversely extending end portions of the base member extending downwardly from said body portion.

2. A roasting rack according to claim 1, in which each corner portion of the base member comprises an inverted U-shape bend each merging with a horizontal wire portion which horizontal wire portions extend toward each other in the vertical plane of the respective head portion.

3. A roasting rack according to claim 1, in which each corner portion of the base member comprises an inverted U-shape bend each merging with a horizontal wire portion which horizon-

tal wire portions extend towards each other in the vertical plane of the respective head portion, with the addition that each of the inverted U-shape bends has an inward protrusion formed by a swedge-pinched deformation serving as a stop for the respective side members so as to determine the extreme outwardly swung positions thereof.

4. A roasting rack according to claim 1, in which said loop portions of the base member are in the form of individual although identical wire loop members, with the addition of a longitudinally and medially extending sleeve member surrounding and swedge-connected to the terminal portions of said loop members for interconnecting said loop members.
